Primary Examiner — Michelle E. Wilson*Assistant Examiner* — Caitlin A Laverty(74) *Attorney, Agent, or Firm* — Jonathan M. Rixen; Charles A. Lemaire; Lemaire Patent Law Firm, P.L.L.C.(57) **CLAIM**

The ornamental design for an earpiece-foam sizing tool, as shown and described.

DESCRIPTION

FIG. 1 is a perspective top view of the decorative earpiece-foam sizing tool showing the new design;

FIG. 2 is a left side view thereof;

FIG. 3 is a top view thereof;

FIG. 4 is a rear side view thereof;

FIG. 5 is a front side view thereof;

FIG. 6 is a right-side view thereof; and,

FIG. 7 is a bottom view thereof.

In all of the Figures, any broken lines are for the purpose of illustrating portions of the earpiece-foam sizing tool that are not part of the claimed design.

1 Claim, 3 Drawing Sheets(56)
